UNITED STATES PATENT OFFICE.

CYRUS CHAMBERS, JR., OF OVERBROOK, PENNSYLVANIA.

COTTER.

No. 895,842.

Specification of Letters Patent.

Patented Aug. 11, 1908.

Application filed September 27, 1906. Serial No. 336,445.

To all whom it may concern:

Be it known that I, CYRUS CHAMBERS, Jr., a citizen of the United States, residing at Overbrook, in the county of Montgomery 5 and State of Pennsylvania, have invented a new and useful Cotter, of which the following is a specification.

My invention relates to improvements in cotters.

10 The object of this invention is to provide a ready and economical means for securing in place the working parts of machinery.

My improved cotter is adapted to be used 15 in place of solid pins, split pins, linch pins, jam nuts and the like.

The ordinary split pin or cotter pin is frequently objectionable for one or more of the following reasons; because of the very limited amount of wearing surface exposed to 20 the moving parts, because of the liability to rust fast and become practicably immovable, because of the difficulty and expense of drilling the stud or shaft centrally and in line with the face of the working parts and because of the difficulty of entering the cotter into the hole prepared therefor, and the liability of its working out unless the split end 25 is spread open, in which case it is difficult to get out.

30 The purpose of my invention is to obviate all of the above recited objections.

Referring to the drawings:—Figure 1 is a front elevation of one form of my cotter. Fig. 2 is a side elevation of same. Fig. 3 is a front elevation of a cotter with associated mechanism. Fig. 4 is a side elevation of same. Figs. 5, 6, 7 and 8 are front elevations of modified forms of cotters. Fig. 9 is a front elevation of the cotter shown in Fig. 40 8 with associated mechanism. Fig. 10 is a side elevation of same. Fig. 11 is a front elevation with a different form of associated mechanism. Fig. 12 is a side elevation of same. Figs. 13, 14, 15 and 16 are different 45 forms of cross-section of metal from which the cotter may be made. Fig. 17 is a front elevation of a cotter in connection with a nut. Fig. 18 is a side elevation of same. Fig. 19 is a section on line x—x of Fig. 17.

50 Similar numerals refer to similar parts throughout the several views.

The simplest form of my cotter is shown in Figs. 1, 2, 3 and 4, having a bowed portion 21 at the top and oppositely disposed symmetrical curved portions 22, for embracing and clamping the stud. The flaring ends 23

are provided for convenience in springing the cotter over the stud. The cotter is made preferably of spring metal of any convenient form of cross-section, that is, it may be made 60 of round wire as shown in cross-section in Fig. 13, round wire flattened as shown in cross section in Fig. 14, square wire as shown in Fig. 15 or narrow strips of sheet metal cut wider than the thickness of same, as shown in Fig. 16.

I turn an annular groove or channel in the stud, axle or bolt 24, as the case may be, sufficiently wide to admit of the width of the wire of which the cotter is made, and of such depth as to give a good shoulder to retain the open cotter in place, or of such diameter that the cotter will spring on it and close tight around the neck thereof. The bow 21 and the ends 23 of the cotter project beyond 75 the groove to maintain the moving parts of the machinery, such as a wheel or friction roller 26, connecting rod 27, or nut 28, in the required relative position.

In the construction shown in Fig. 11, the 80 bow is so formed that the interior extensions or members thereof shall be true arcs when sprung to the proper diameter, and an outside extension or member thereof bent to conform to an arc concentric with the arcs 85 of the interior members, and embracing say three fourths of the complete circle thereof, the said concentric extensions or members connected by return bends, whereby the whole is allowed to occupy but little room 90 around the stud or bolt, or beyond the surface thereof yet allowing great resiliency for the springing of the cotter over the neck of the stud or bolt. Sometimes it is desirable to have a wheel or nut secured on the stud 95 or bolt so as to resist great force in the tendency of the same to come off. In such cases I make a spring cotter of square wire, or wire whose thickness is less than the width thereof, or in other words bent edgewise, so 100 that, when a groove is turned in the stud or bolt, the cotter will only bury itself half the depth of the width of the wire, thus permitting one half to lock itself in the groove and leaving the other half projecting to form a 105 collar to prevent the roller or nut from coming off, see Fig. 17. In a construction of this character the cotter would have to be sheared throughout the whole length embracing the neck of the stud or bolt before 110 it would let go, as clearly shown in section and side elevation.

The various forms of the bow of the cotter are to adapt the device to various requirements, those requiring more resiliency are formed with the greater number of coils or folds, varying in length to suit the situation.

What I claim is:—

1. A cotter having coöperating clamping extensions, and an intermediate spring for actuating same, as the sole means for maintaining the cotter in position.
2. In combination with a recessed or shouldered shaft, a cotter having coöperating clamping extensions, and an intermediate spring for actuating same, as the sole means for maintaining the cotter in position on the shaft.
3. The combination of a cotter, and a shaft provided with an annular channel, the cotter formed with oppositely curved embracing extensions, and an intermediate resilient bow, the embracing extensions adapted to seat in the annular channel as the sole means for engaging the cotter with the shaft.
4. A cotter consisting of a single strip of metal, including in its extension arcs of substantially the same circle, and a resilient bow intermediate two arcs, in combination with a shaft having an annular channel for receiving said arc portions, the resilient co-operation of the arcs in the channel being the sole means for securing the cotter to the shaft.
5. In combination with a shaft provided

with an annular channel, a cotter consisting of a single strip of metal formed with portions of its extension in arcs of substantially the same circle, with a spring bow therebetween, the arc extensions adapted to seat in the annular channel, as the sole means for engaging cotter with shaft, said arc extensions having a transverse dimension greater than the depth of the channel.

6. A spring cotter, provided with a curved extension or surface, and a coöperating oppositely disposed extension to form a clamp therewith, spring means for connecting said two extensions, comprising resilient extensions lying in concentric arcs.

7. A spring cotter, provided with embracing extensions and an intermediate bow so formed that the interior members thereof shall be in arcs of true circles when sprung to the proper diameter, and an outside member thereof in the arc of a concentric circle embracing approximately three-quarters of the circumference thereof, whereby the whole is allowed to occupy but little space around the stud or bolt, or beyond the surface thereof, yet allowing great elasticity for the springing of the cotter over the neck of the stud or bolt.
